UNITED STATES PATENT OFFICE

106,014

DESIGN FOR A MERCHANTISE CASE

Charles Ralph Anderson, Rock Island, Ill.

Application January 15, 1937, Serial No. 67,080

Term of patent 14 years

To all whom it may concern:

Be it known that I, Charles Ralph Anderson, a citizen of the United States, residing at Rock Island, in the county of Rock Island and State of Illinois, have invented a new, original, and ornamental Design for a Merchandise Case, of which the following is a specification, reference being had to the accompanying drawing, forming a part thereof.

Fig. 2 is an end perspective view thereof.

The design is especially characterized by the provision of a front wall comprising two portions slanting at different respective angles, substantially as shown.

I claim:

The ornamental design for a merchandise case substantially as shown and described.

CHARLES RALPH ANDERSON.
